* cited by examiner

Primary Examiner — Catherine S Posthauer*Assistant Examiner* — Alison M Ofstun(74) *Attorney, Agent, or Firm* — Barnes & Thornburg LLP(57) **CLAIM**

I claim the ornamental design for a clip on plug, as shown and described.

DESCRIPTION

FIG. 1 is a front perspective view of a clip on plug, showing my new design;

FIG. 2 is a front elevational view thereof;

FIG. 3 is a rear elevational view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a rear perspective view thereof.
